APPARATUS FOR DISENTANGLING TANGLED SPRINGS AND THE LIKE

F. Bradley Stevens, Ann Arbor, Mich., assignor to Associated Spring Corporation, Bristol, Conn., a corporation of Delaware

Filed Apr. 10, 1964, Ser. No. 358,822
11 Claims. (Cl. 214—1)

This invention relates broadly to articles of manufacture such as springs, electric heating coils, and the like, which are formed of wire or rod coiled into helical shape, and to the manufacture and processing thereof, and more particularly to means for separating two or more of such articles which have become entangled and tightly meshed with one another. In this specification and in the appended claims all such articles of manufacture of helical form will be referred to by the generic term "springs."

Any such springs, particularly those having spaced convolutions, may become entangled with one another when thrown together as they usually are in the several stages of manufacture and during bulk shipment to the point of use, the usual entanglement being in side-by-side relation with the convolutions of the two springs interleaved and often, or usually, with the springs an angularly related positions. The tangled springs must be separated for use or for the performance of secondary operations, which separation adds to the cost of the springs, regardless of whether it is done before or after delivery by the manufacturer to the user.

It has accordingly been the object of this invention to provide a simple and effective device for separating the tangled springs of a cluster. The disentangling means provided by the invention may be associated with any means for separating single springs from tangled clusters of springs, such, for example, as apparatus by which the springs are fed continuously to the disentangler as they come from a bulk supply of springs, or from any other source, and which may be operative to reject the single, untangled springs and accept all clusters of tangled springs for separation by the disentangling device provided by the invention.

Description of the drawings

FIG. 1 is a side elevational view of the device provided by the invention for separating the tangled springs of a cluster of interleaved helical springs;

FIG. 2 is an end view of parts shown in FIG. 1, taken on line 2—2 of FIG. 1, and

FIGS. 3 and 4 are perspective views each showing a cluster of two tangled springs in possible positions on the supporting rollers forming part of the separating device provided by the invention, and illustrating the operation thereof.

The invention provides means for supporting each cluster of tangled springs and positioning it for engagement by a device which separates the tangled springs A, B of the cluster. This supporting and positioning device comprises two rollers 2, 4 which are supported by suitable means in parallel, side-by-side relation, laterally spaced apart with roller 4 slightly below the other roller 2, the lateral spacing between the rollers being such that a cluster of helical spring of the size being manufactured or handled will be supported by the two rollers, all as most clearly illustrated in FIG. 2. The upper roller 2 is not mounted for rotation but will be referred to as a roller in this specification. Roller 4 is mounted for rotation and is connected by a pulley 6 and belt 8 to some means, such as an electric motor for imparting rotation to it in such a direction that its upper part moves away from the upper, non-rotating roller 2. The outer surface

2

of roller 4 is polished and smooth throughout the greater part of its length and at its one end is circumferentially recessed and the recess is filled with an annular ring of friction material 10, the outer surface of which is below the outer surface of the remainder of the roller.

The means provided by the invention for engaging and separating the two springs of a cluster supported on the rollers 2, 4 are particularly disclosed in FIG. 1 and comprise a two-pronged lance device consisting of two parallel laterally spaced rod-like lances 20, 22 which are mounted, one above the other, on a head 24 carried by the rod 26 of a piston 28 mounted for reciprocal movement in a cylinder 30 which is supplied with compressed air or hydraulic fluid through pipes 32, 34. The two lances 20 and 22 and the supporting and reciprocating structure are so mounted that the lances are parallel to the upper supporting surfaces of the rollers 2, 4 and are normally spaced outwardly therefrom so that when the lances are moved toward the rollers the lower lance 20 will enter the lower one of two tangled springs of the cluster while the upper lance 22 will enter the upper spring. The lower lance 20 is longer than the upper lance 22 and has a pointed end provided by an upwardly facing bias surface 36. The outer end of the upper lance 22 is also pointed and this pointed end part is bent downwardly toward the lower lance 20, providing an outwardly and downwardly inclined leading edge surface 38 at the outer end of this lance. The outside diameter of the lower lance 20 is approximately equal to, but slightly less than, the inside diameter of the springs being processed, while the upper lance 22 has a much smaller outside diameter.

Adjacent and spaced from the ends of the rollers 2, 4 opposite to the ends from which the lances approach, there is provided a vertical stop plate 40 against which the cluster of springs supported by the rollers is moved by the lances, thus facilitating the entry of the lances into the springs and preventing the springs from being moved axially from the rollers. The stop plate may be provided with openings 42, 44 through which the lances may pass.

Operation

A cluster of two tangled springs A and B which is to be subjected to separation by means provided by this invention is positioned on the roller 2, 4, as shown in FIGS. 1 and 2. The delivery of such a cluster to these rollers may be accomplished in a variety of means and devices which do not form part of this invention.

In FIGS. 1 and 2 of the drawings there is shown a cluster of two tangled springs A, B properly positioned on the rollers 2, 4 for separation by the lance devices. It will be seen that in this position of the cluster spring A lies on and nestles between the roller with its axis parallel to those of the rollers. If the cylinder and piston apparatus 28, 30 is operated the lower lance 20 will enter spring A and substantially fill it, and the bias face 36 forming the leading edge of this lance will engage the outer surface of the second spring B and force this spring outwardly of spring A. The upper lance 22 now enters spring B and the inclined leading edge 38 of the upper lance engages the upper part of the inner surface of the upper spring and forces it away from the lower spring and out of engagement therewith. The lance device will then be retracted and the springs will fall free of each other and of the rollers 2, 4, although the springs may be forcibly moved from the rollers by some such means as a blast of air.

As stated above, the disentangling apparatus provided by the invention and described above may have associated with it any means or device for delivering clusters of tangled springs to the rollers 2, 4 and positioning each cluster thereon for engagement by the lance device.

When springs enmesh, their axes are almost never in parallel alignment, there generally being a considerable angle between the two, nor does a cluster of tangled springs always fall on the rollers 2, 4 in the proper position for lancing which is shown in FIGS. 1 and 2. In such cases, before the lower lance of this machine can perform its function, it is necessary that one spring of the crossed axis pair be moved to a position parallel with and between the two rollers with the other member more or less above the first one and pointing diagonally in one direction or another. This position of the spring cluster is shown in FIG. 1 of the drawings. When a cluster is dropped on to the rollers one of the members will fall in this desired position nestled between the rollers a high proportion of the time. In this position it is impossible for the polished rotating surface 10 of roller 4 to exert sufficient grip to roll the cluster over and out of lancing position since any rolling would entail lifting as well, this being the reason the surface of roller 4 is hardened and polished. The friction surface 10, on the other hand, can do this and therefore it is recessed so that if the bottom spring of the combination is toward the stop plate rather than the lance and nestled between the rollers, it will be supported on the polished surfaces in a position parallel to and above the friction surface, and will not be engaged and rolled.

In the remainder of the cases the angled cluster falls in either one of two ways. In the first of these, which is illustrated in FIG. 3, the two ends of the cluster point into the opening between the rollers and its nexus lies on top of the lower roller. In this position the traction surface 10 operates on the end of one of the springs, rotating it out of the crevice and causing the other spring, the one nearest the lances, to nestle between the polished surfaces. Rotation of the cluster ceases immediately when the one end swings up eccentrically out of contact with the traction surface. In the second position, which is shown in FIG. 4, the nexus is on the lower roller and the ends of the cluster are up in the air. Contact with the rotating polished roller is sufficient under these circumstances to turn the cluster over, since all weight is concentrated on one or two points, the ends are uninhibited and no lifting is involved. When one end swings around far enough to contact the lower roller at the stop plate end, the traction surface finishes the job as in the first case. Thus, the roller system as described, exerts a position ameliorating effect on all clusters, which effect stops automatically when the cluster is in proper position for entry by the lower lance.

When the bottom spring is nestled, the cluster is not necessarily in position for the upper lance to enter. The upper spring inside diameter may be located radially with respect to the lower spring anywhere within a 90° to 120° sector and not opposite the upper lance. A full diameter lower lance with a long bias face is necessary for the next stage of positioning. The long taper is desirable for reaching under overhanging upper springs, which may project a considerable distance toward the lance, without tipping the cluster out of nestled position. The thin edge is needed for insinuating between the inside diameter of the lower spring and the coils of a deeply enmeshed upper spring. The bias face forces the two out of deep mesh into peripheral mesh but, more important, it acts upon the upper spring causing the whole cluster to rotate until the upper spring is directly above the bias face and in ideal position for the upper lance to enter the lower spring and move the two springs out of peripheral mesh. If the lower lance were less than full diameter, clusters of only shallow mesh would never receive this orienting action and the upper lance would frequently miss the upper spring.

While I have described and illustrated one form which my invention may take, it will be apparent to those skilled in the arts to which it relates that other embodiments, as well as modifications of that disclosed, may be made and

practiced without departing in any way from the spirit or scope of the invention, for the limits of which reference must be made to the appended claims.

What is claimed is:

- 5 1. Apparatus for separating tangled helical springs and the like, comprising two spaced substantially parallel rod-like lances one of which is straight and the other of which has an end part bent toward the first, means for moving said rods forwardly together in the direction of their free ends and in the reverse direction, and means for supporting a tangled cluster of two laterally interleaved springs in position for the two springs to be penetrated in generally axial direction, one by each lance, on the forward movement thereof to thereby separate the springs.
- 10 15 2. Apparatus for separating tangled helical springs according to claim 1, in which the lance which has an end part bent toward the other is shorter than the other.
- 20 3. Apparatus for separating tangled helical springs and the like according to claim 1, comprising in addition stop means positioned to engage the end of a tangled cluster of springs to hold the same from axial movement as the springs are penetrated by the lances.
- 25 35 4. Apparatus for separating tangled helical springs and the like, comprising two spaced substantially parallel rod-like lances one of which is straight and the other of which has an end part bent toward the first, means for moving said rod forwardly together in the direction of their free ends and in the reverse direction, means for supporting a tangled cluster of springs in general axial alignment with
- 30 35 30 said lances, means for rotating the supported tangled cluster to a position in which the two springs of the cluster are respectively aligned with the two lances, whereby said springs may be penetrated in generally axial direction, one by each lance, on the forward movement thereof to thereby separate the springs.
- 40 45 5. Apparatus for separating tangled helical springs and the like, comprising two spaced substantially parallel rod-like lances one of which is straight and has a biased outer end surface and the other of which has an outer end part bent toward the first lance, means for moving said lances forwardly together in the direction of their outer ends and in the reverse direction, and means for supporting a tangled cluster of two laterally interleaved helical springs in position for the two springs to be penetrated in generally axial direction, one by each lance, on the forward movement thereof to thereby separate the springs.
- 50 55 6. Apparatus for separating tangled helical springs and the like, comprising two spaced substantially parallel rod-like lances one of which is straight and has a biased outer end surface and the other of which has an outer end part bent toward the first lance, means for moving said lances forwardly together in the direction of their outer ends and in the reverse direction, said lances being spaced vertically one above the other, the lower lance having a thickness approximately equal to the inside diameter of the springs being processed and having at its outer or leading end an upwardly facing bias surface disposed at an angle to the axis of the lance, and means for supporting a tangled cluster of two laterally interleaved helical
- 60 70 60 springs in position for the two springs to be penetrated in generally axial direction, one by each lance, on the forward movement thereof to thereby separate the springs.
- 65 75 7. Apparatus for separating tangled helical springs and the like, comprising two spaced substantially parallel rod-like lances, means for moving said lances forward together in the direction of their outer ends and in the reverse direction, said lances being spaced vertically one above the other, the lower lance being straight throughout its length and having a thickness approximately equal to the inside diameter of the springs being processed and having at its outer or leading end an upwardly facing bias surface disposed at an angle to the axis of the lance, the upper lance being of substantially less thickness than the lower lance and being straight throughout substantially

all of its length and at its outer or leading end having an end part bent toward the lower lance, and means for supporting a tangled cluster of two laterally interleaved helical springs in position for the two springs to be penetrated in generally axial direction, one by each lance, on the forward movement thereof to thereby separate the springs.

8. Apparatus for separating tangled helical springs and the like, comprising two spaced substantially parallel rod-like lances one of which is straight and has a biased outer end surface and the other of which has an outer end part bent toward the first lance, means for moving said lances forwardly together in the direction of their outer ends and in the reverse direction, and means for supporting a tangled cluster of two laterally interleaved helical springs in position for the two springs to be penetrated in generally axial direction, one by each lance, on the forward movement thereof to thereby separate the springs, said supporting means comprising two parallel coextensive rollers positioned in substantially side-by-side relation to form surfaces for supporting a tangled cluster of springs, said rollers being axially parallel to said lances and laterally positioned with respect thereto so that the springs of a tangled cluster supported by said rollers will be respectively aligned with said lances.

9. Apparatus for separating tangled helical springs and the like, comprising two spaced substantially parallel rod-like lances, said lances being spaced vertically one above the other, the lower lance being straight throughout its length and having a thickness approximately equal to the inside diameter of the springs being processed and having at its outer or leading end an upwardly facing bias surface disposed at an angle to the axis of the lance, the upper lance being of substantially less thickness than the lower lance and being straight throughout substantially all of its length and at its outer or leading end having an end part bent toward the lower lance, means for moving said lances forwardly together in the direction of their outer ends and in the reverse direction, and means for supporting a tangled cluster of two laterally interleaved springs in position for the two springs to be penetrated in generally axial direction, one by each lance, on the forward movement thereof to thereby separate the springs,

said supporting means comprising two parallel coextensive rollers positioned in substantially side-by-side relation to form surfaces for supporting a tangled cluster of springs, said rollers being axially parallel to said lances and laterally positioned with respect thereto so that the springs of a tangled cluster supported by said rollers will be respectively aligned with said lances, and means for rotating one of said rollers in such a direction that the upper part thereof moves away from the other roller.

10. Apparatus for separating tangled helical springs and the like, comprising two spaced substantially parallel rod-like lances one of which is straight and has a biased outer end surface and the other of which has an outer end part bent toward the first lance, means for moving said lances forwardly together in the direction of their outer ends and in the reverse direction, means for supporting a tangled cluster of two laterally interleaved springs in position for the two springs to be penetrated in generally axial direction, one by each lance, on the forward movement thereof to thereby separate the springs, said supporting means comprising two parallel coextensive rollers positioned in substantially side-by-side relation to form surfaces for supporting a tangled cluster of springs, said rollers being axially parallel to said lances and laterally positioned with respect thereto so that the springs of a tangled cluster supported by said rollers may be respectively aligned with said lances, and means for rotating one of said rollers in such a direction that the upper part thereof moves away from the other roller, one of said rollers having a recessed friction surface at one end thereof for engaging one of the springs of a tangled cluster to rotate the cluster to position the springs of the cluster to be penetrated by the lances.

11. Apparatus for separating tangled helical springs and the like according to claim 10, in which the rotating roller is positioned below and to one side of the other roller and said other roller is non-rotatable.
